WELL PACKER

George Green, Houston, Tex.

Application October 6, 1945, Serial No. 620,710

11 Claims. (Cl. 166—12)

1

This invention relates to new and useful improvements in well packers.

One object of the invention is to provide an improved well packer which may be readily lowered into a well and secured in position without orienting, unlatching or screwing or unscrewing parts thereof.

A further object of the invention is to provide an improved packer having slips for setting it in position and means for actuating said slips; together with means which may be used to jar the slip actuating means to release the slips.

Another object of the invention is to provide an improved packer including a separable housing and a two-part mandrel arranged so that one mandrel part may be utilized to actuate the slips and the other mandrel part used to jar the slip actuating mandrel to release the slips or to separate the housing and remove the upper portion in case the slips cannot be released.

A still further object of the invention is to provide a packer with an upper and a lower mandrel wherein the upper mandrel forms part of a by-pass valve, a jar for releasing the slips and means for orienting the housing to separate it.

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is a half section and elevation of the upper portion of a packer constructed in accordance with the invention.

Fig. 2 is a similar view of the lower portion of said packer.

Figs. 3, 4 and 5 are horizontal cross-sectional views of the packer, taken on their respective lines and

Fig. 6 is a sectional detail of one of the bow springs.

In the drawings, the numeral 10 designates generally a cylindrical housing of substantially uniform external diameter and including an upper or head section 11 and a lower or slip section 12. At its lower end, the section 11 is provided with an internally screw-threaded tapered socket 13 into which is screwed a tapered screw-threaded pin 14, which latter is provided with an annular shoulder 15 at its base engaging the lower edge of the member 11 so as to provide a tight joint. The housing is tubular

2

and a tubular slip mandrel, indicated generally by the numeral 16, is slidable therein and externally screw-threaded at its lower end so as to be screwed into a perforated bull plug strainer 18.

At its medial portion, which is within the section 12, the mandrel is formed on its outer surface with upwardly and inwardly inclined annular expansion rings 19 which are integral therewith and are disposed vertically in stepped order. These rings constitute slip displacing elements. The lower end of the lowermost ring is surrounded by an annular stop shoulder 20. The section 12 is formed with vertical windows 21 spaced equi-distant in the circumference of said section, three of such windows being shown, but the number being optional. Vertical slips 22 are disposed in these windows and each slip has upon its rear face inclined surfaces 23 complementary to the rings and engaging the same so that upon vertical movement of the mandrel the slips may be expanded and retracted. The inclined faces 23 are of such lengths as to permit vertical movement of the rings with respect to such surfaces. The slips are provided with vertical rows of teeth 24 for engaging the inner surface of a well pipe. When the mandrel is in its lowermost position, the teeth of the slips will be retracted within the external diameter of the section 12 and when the mandrel is moved upwardly, the rings 23 will cause the slips to be radially expanded out through the windows 21, whereby the teeth 24 will bite into the inner surface of a well pipe and fasten the packer in position. For limiting the outward or radial movement of the slips, each one is provided at its upper end with an inwardly directed recess 25 for receiving the lower end of a keeper 26 countersunk in the surface of the section 12 at the upper end of its respective window and secured by a machine screw 27. Each slip has a depending lug 28 at its lower end co-acting with the keeper to limit the outward movement of the slip. The slips 22, the rings 23 and the mandrel 16, constitute anchoring means for anchoring the packer in a well casing.

Below the rings 19, the mandrel 16 is formed with an annular enlargement 29, the base of which is surrounded by an undercut annular collar 30. Below the collar 30, the mandrel is formed into a reduced tubular shank 31 and the bull plug 18 is screwed onto the lower end of this shank. A pair of elastic packer cups 32 are mounted on the shank 31, one above the other. These cups are substantially duplicates,

and may be made of synthetic rubber, rubber or any other material suitable for the purpose. Each cup has its upper annular end beveled as is indicated at 33. The bevel 33 of the upper cup engages the undercut surface of the collar 30 and the external diameter of said cup is substantially the same as the diameter of said collar. An annular thimble 34 is mounted on the shank 31 and is provided with an undercut surface 35 which is engaged by the bevel 33 of the lower cup. The upper edge portion of the thimble is beveled and the thimble supports a relatively thin sleeve 36, which has a snug sliding fit on the shank 31 and telescopes the upper cup, as is shown in Fig. 2.

The lower end of each cup is formed with an outwardly offset annular lip 37, which has an external diameter greater than the diameter of the body of the cup so as to engage the inner wall of a well pipe. The lip of each cup is spaced outwardly so that pressure fluid may enter the lower end of the cup and expand it. The lower cup is supported by a sleeve 38, similar to the sleeve 36, resting upon the bull plug 18. It is obvious that when the bull plug is screwed up against the lower sleeve 38, the packer assembly is adequately secured on the shank 31 and may be removed therefrom when desired.

A tubular operating mandrel or movable member 39 is disposed to slide vertically in the head section 11. This mandrel may be referred to as a head mandrel because it is in the head section. The head section is formed with counterbores 40, 41 and 42, each of reduced diameter, upwardly of said section. The upper end of the section is formed with a short bore 43 in which the mandrel 39 is slidably. Elongate vertical splines 44 are provided on the mandrel and engage in vertical guideways 45 in the bore 43, whereby the mandrel 39 is free to slide vertically. The splines are long enough to remain in the guideways at all vertical adjustments of the operating mandrel, so that rotation may be contributed to the housing section 11 upon rotation of said mandrel. The upper end of the mandrel extends above the housing 16 and is provided with a screw-threaded pin 46 for attachment to an operating pipe.

The lower end of the mandrel 39 is formed with an annular externally screw-threaded head 47 having an overhanging annular flange 48 at its upper end. A fluid-pressure sealing ring 49 is fitted around the head and engages under the flange. An internally screw-threaded collar 50 is screwed onto the head below the ring and has ports 51 which register with radial ducts 52 extending transversely through the head from the bore of the mandrel 39. It will be noted that the upper end of the packer mandrel 16 has an annular neck 53 which has a sliding fit in an axial bore 54, formed in the upper end of the section 12. Within the pin 14, an annular recess 55 is provided for receiving a fluid-pressure packing ring 56 which snugly engages the neck 53 to form a fluid-tight joint.

The head 47 including the elements carried thereby, is of such external diameter as to have a sliding fit when moved upwardly into the counterbore 41. With the parts in the position shown in Fig. 1, it will be observed that fluid flowing in the bore of the mandrels 16 and 39 is free to escape through the ducts 52 and ports 51 into the counterbore 40 and thence upwardly through the counterbores 41 and 42, from which latter it may escape through radial ducts 57 into the pipe or

tubing surrounding the packer. These elements form a by-pass and a by-pass valve, whereby the packer may be lowered or vertically adjusted in fluid in a well pipe. When the mandrel 39 is moved upwardly, the ring 49 will seal against the annular wall of the bore 41 and thereby shut off the by-pass. It will also be observed that the head 47 of the mandrel may be engaged with the neck 53 of the mandrel 16 to force the same downwardly and thereby permit the slips 22 to retract.

In lowering the packer into a well, upward fluid-pressure may be exerted within the lips 37 of the cups 32, which will tend to move the mandrel 16 upwardly and expand the slips; however, if the weight of the mandrel 39 and the tubing attached thereto is imposed upon the mandrel 16, said slips will not be expanded into gripping engagement with the well pipe, but if the mandrel 39 is lifted and the by-pass closed, then the fluid-pressure acting upon the cups 32 will move the mandrel 16 upwardly and expand the slips 22 into gripping position. Once the slips are set, the mandrel 39 may be freely moved vertically. If the section 12 should become locked in the well, the mandrel 39 may be rotated and this will contribute rotation to the splines 44, whereby the head section 11 may be rotated and unscrewed from the pin 14. This will permit the upper section 11 to be withdrawn from the well and the lower section 12 fished out in accordance with the usual practice.

In order to prevent the housing 10 from moving downwardly independently of the mandrel 39, whereby the mandrel 16 would be separated therefrom and the slips 22 inadvertently set, I provide a plurality of retarding elements in the form of elongate flat springs 58 disposed in complementary recesses 59 in the surface of the section 12 between the windows 21. The upper ends 40 of these springs are fastened by screws 60. These springs are bowed so that their medial portions will project outwardly from the outer surface of the housing and ride the inner annular surface of the well casing, while their lower ends are free so that said springs may be depressed into said recesses and yield to irregularities in the casing surface.

It is pointed out that when it is desired to retrieve the packer after it is set in a well, it is only necessary to lift the mandrel 39 and then use it as a jar to hammer down on the mandrel 16 which will drive the mandrel 16 downwardly, whereby the rings 19 will be lowered, thus releasing the slips. If the slips cannot be released in this manner the mandrel 39 is oriented whereby the splines 44 will unscrew the upper housing section 11, as hereinbefore described.

When the packer is lowered in a well the springs 58 will ride the inner annular surface of the well casing (not shown), whereby the housing 10 will be sufficiently retarded to keep the mandrels 16 and 39 in contact and prevent the slips 22 from setting; also the head 47 will be held down so as to keep open the by-pass formed by the elements 52, 51, 40, 41, 42 and 51. When the proper location is reached, the mandrel 39 is lifted, while the housing is held substantially stationary by the springs 58. When the mandrel 39 is lifted, the head 47 will be raised into the counterbore 41, whereby the pressure seal packing ring 49 will be shut off the by-pass. The fluid pressure will act upon the cups 32 and thus lift the mandrel 16, whereby the rings 19 will radially displace the

slips 22 and causing their teeth 24 to bite into the casing wall.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A removable well packer including, an elongate outer tubular housing having slip openings therein, a tubular slip mandrel free to slide longitudinally in said housing and having slip displacing elements thereon, slips in the housing displaceable through the housing openings engaged by the displacing elements of the slip mandrel, whereby said slips are displaced radially outwardly by the displacing elements upon upward longitudinal movement of the mandrel relative to the housing and slips, an external packer member carried by the slip mandrel below the housing, fluid by-pass means in the housing above the slip mandrel for by-passing fluid from the tubular mandrel through the housing to the exterior thereof above the slips and the packer member, and a member movable longitudinally in the housing above the slip mandrel and having a well tool connection at its upper end and adapted to engage and move said mandrel downwardly relative to said slips.

2. A removable well packer as set forth in claim 1, and means carried by the movable member and engaging the housing for rotating the housing when said movable member is rotated.

3. A removable well packer as set forth in claim 1, in which the housing is made up of separate interconnected sections, one of which sections carries the slip mandrel and slips and the other section carries the by-pass means and the movable member.

4. A removable well packer including, a tubular housing having slip windows, slips movable radially through the housing windows, a tubular slip mandrel movable longitudinally in the housing and extending therebelow, said slip mandrel having means thereon for radially moving the slips outwardly into engagement with the inner surface of surrounding well pipe as the slip mandrel moves upwardly relative to the slips, an external packer member on the slip mandrel below the housing frictionally engageable with a surrounding well pipe, a head mandrel extending into and longitudinally slideable in the housing above the slip mandrel and adapted to engage and move said slip mandrel downwardly relative to the housing to release the slips from engagement with the surrounding well pipe, the housing and the head mandrel having means for establishing a fluid by-pass therethrough, and valve means carried by the head mandrel engageable with a valve seat on the tubular housing for closing off the by-pass means.

5. A removable well packer as set forth in claim 4, wherein the housing is made up of upper and lower interconnected separable sections, and connection means carried by the mandrel and engaging the upper section for transmitting rotation from the mandrel to said section when the mandrel is rotated and the lower section is held against rotation.

6. A removable packer including, a lower housing section having a screw-threaded member at its upper end, an upper housing section having screw-threads at its lower end engaging said

member, anchoring means carried by the lower housing member, an external packer member supported from and below the lower housing section below the anchoring means, the upper housing section having a bore and a counterbore, and a tubular mandrel movable vertically in the bore and counterbore of the upper housing for engaging and releasing the anchoring means and also having means for engaging and 10 rotating the upper housing section to unscrew it from the lower section.

7. A removable packer as set forth in claim 6, and shut-off means on the mandrel for engaging in the counterbore of the upper section and 15 closing off the bore thereof when the mandrel is moved vertically.

8. A removable well packer including, a tubular housing made up of an upper section and a lower section having screw connection with and 20 separable from the upper section, anchoring means carried by the lower section having slips for anchoring the latter in a well, exterior packing means carried by the anchoring means below the slips, a head mandrel in the upper housing section and movable longitudinally therein for engaging and releasing the anchoring means, said head mandrel having slideable engagement with the upper section for rotating and unscrewing said upper section to separate it from 25 the lower section when said lower section is held against rotation.

9. A removable packer as set forth in claim 8 with means in the housing and head mandrel for by-passing fluid through the housing, and 30 means on the mandrel for closing off the by-pass means.

10. A removable packer including, a tubular housing made up of an upper section and a lower section having screw-threaded connection with 35 and separable from the upper section, anchoring means carried by the lower section having slips for anchoring the latter in a well, exterior packing means carried by the anchoring means below the slips, a head mandrel in the upper housing section and movable longitudinally therein for engaging and for releasing the anchoring means, inter-engaging means on the mandrel and in the upper section for rotating the upper section when the lower section is held 40 against rotation for unscrewing the sections, the head mandrel being tubular and having a lateral passage therethrough, the upper section having a lateral passage and a counterbore between its passage and the lateral passage of the mandrel, 45 and shut-off means on the mandrel adapted to close the counterbore of the upper section to shut off communication between the passages when the mandrel is moved longitudinally.

11. A removable well packer including, a tubular housing, slips carried by the housing and held against longitudinal movement with respect to the housing, said slips being radially movable, a tubular slip mandrel movable longitudinally in the housing and extending therebelow, said 50 slip mandrel having means thereon for radially moving the slips outwardly into engagement with the inner surface of surrounding well pipe as the slip mandrel moves upwardly relative to the slips, an external packer member on the slip mandrel below the housing frictionally engageable with the surrounding well pipe, a head mandrel extending into and longitudinally slideable in the housing above the slip mandrel and adapted to engage and move the slip mandrel 55 downwardly relative to the housing to release

the slips from engagement with the surrounding well pipe, the housing and the head mandrel having means for establishing a fluid by-pass therethrough, and valve means carried by the head mandrel engageable with a valve seat on the tubular housing for closing off the by-pass means.
